UNITED STATES PATENT OFFICE.

JAMES S. COPELAND, OF HARTFORD, CONNECTICUT, ASSIGNOR TO THE
POPE MANUFACTURING COMPANY, OF PORTLAND, MAINE.

VELOCIPED.

SPECIFICATION forming part of Letters Patent No. 412,322, dated October 8, 1889.

Application filed May 21, 1888. Serial No. 274,509. (No model.)

To all whom it may concern:

Be it known that I, JAMES S. COPELAND, of Hartford, in the county of Hartford and State of Connecticut, have invented certain new and useful Improvements in Velocipedes, of which the following is a specification.

My present improvements relate more particularly to the frame-work and steering and brake mechanism of tricycles and safety-velocipedes, and are especially applicable in connection with the steering-handles and guiding-wheel fork of such machines; but they are also applicable, with such modifications as might be obvious to any mechanic, in other machines and in other positions than those in which I show and describe their application herein.

The object of my present improvements is to produce an improved spring-frame, an improved steering-head, an improved brake mechanism, a light, effective, comfortable, economical, and practicable mechanism by which the frame and the rider of the velocipede may be relieved from the jars and shocks occasioned by obstructions and inequalities in the path of the machine; and my invention consists in certain constructions and combinations of parts, which will be best understood from the following description and a reference to the accompanying drawings.

In the drawings, Figure 1 shows in side elevation part of the guiding-wheel and frame and the steering-handle, head, and brake mechanism of a safety-bicycle, embodying my improvements in one form. Fig. 2 shows parts of the same in cross-section and top plan on the line *x x* of Fig. 1; and Fig. 3 shows parts of the same in cross-section and top plan on the line *y y* of Fig. 1; and Fig. 4 shows the same things as Fig. 1, except the wheel, in front end elevation.

A is a guiding-wheel; B, the fork spanning the guiding-wheel and connected therewith, in the usual manner, by an axle and bearings.

C is a tubular pillar connected with the fork B, by brazing or otherwise, and on which, at the bottom or near the fork, I place an encircling transverse lug C', and on or near the top end, or at some distance above the lug C', I place another similar encircling transverse lug C².

D is another tubular pillar, which, as I call C the "fore" pillar, I will call the "after" pillar, and which is nearly parallel with the former. Upon or near the lower end of this after pillar D, I place an encircling transverse lug D', and higher up I place on it another transverse encircling lug D², and above the transverse lug D², I place an encircling ring or clip D³, bearing a bracket for a lamp, as at E, and on the opposite or rear side I place a small set-screw f, or similar device.

F is a tubular handle-bar support, in the top of which, as at f', is the transverse handle-bar F', bearing the handles F².

The transverse encircling-lugs C' D', I connect by the fore-and-aft links L L—one on either side of the pillars—by suitable bolts L' and nuts L², with free but steady and adjustable bearings of any known or suitable construction. The encircling transverse lugs C² D², I connect by the fore-and-aft links K K, by means of the bolts K' K' and nuts K² K², in a manner similar to that in which I connect the lower lugs C' D'; but by preference I make the links K K longer than the links L L, for a purpose to be explained further on.

O' is a lug formed on the encircling transverse lug D', bearing a stop in its upper side for the lower end of a steering-spindle O, and above the lug O', I place the lug O², which I form on or as part of an intermediate encircling lug P, attached to the pillar D by brazing or otherwise, and in this lug O² operates a threaded adjusting-bolt O³, which bears at its lower end a seat for the upper end of the steering-spindle O, and which is held in position by the set-nut O⁴, and O⁵ is a neck and O⁶ a reach connecting the main frame of the velocipede with the spindle O.

P is an encircling bracket or lug placed on the pillar D and secured there, and which I construct with the two arms P' P"—one on either side, and each having a stop P² projecting outwardly.

R is a spring, made of round steel wire or rod, bent at its middle part R', which I place in front of the pillar C and beneath the stops P² P² and bend backward, with the arms R², coils R³, forward and downward projecting arms R⁴, and with its ends R⁵ R⁶ secured in the lug C' to the pillar C.

G is a brake - handle lever pivoted in a bracket G' to the handle-bar F', having the handle g' and the disengaging-spring g, and with its shorter end g² pivoted by the pin g³ 5 to the wrist G², and a downward rod G³. This downward rod G³ may be made extensible by a clamp H' in a ball and socket or other device, as H, to one end of a rocking link G⁴. This rocking link G⁴, I pivot by a small bolt 10 g⁴ to one of the links K, at or near its middle part. A second downward rod G⁶ is connected by a wrist G⁵ at its upper end and a pin g⁵ with the other end of the rocking link G⁴, and at its lower end by a wrist G⁷ to the 15 brake-spoon lever G⁸, which may be pivoted or fulcrumed in any usual or suitable manner to the fork B, and having at its other end the spoon G⁹, operating upon the tire of the guiding-wheel.

20 By this construction and arrangement it will now be seen that I have a velocipede-spring-frame mechanism having a fore pillar and an after pillar and connecting-links and a limiting-spring; but I do not claim this construction, broadly, for I am aware that another before me has made a steering-head in two parts, having a fore pillar of tubular form and a solid after pillar or inner pillar sliding in the first and connected to it by two 25 pairs of links; and having also a bent flat spring with one end connected to the arch of the fork and the other end resting beneath the inner pillar, and in which the handle-bar support was connected with the inner pillar; 30 but I construct my two pillars entirely outside of and separate from each other, both of tubes unslotted and unweakened, and in other details and respects, except those I have above mentioned, my devices and combinations are 35 different in their construction and operation. By making the upper links K K longer than the lower ones L L the two pillars are permitted to take a different direction or angular relation with each other under the operation of the machine. Thus if the guiding-wheel encounters an obstruction and is wholly or partially arrested or lifted, the spring yields, the links swing, and the frame and rider are thereby relieved of a portion or 45 50 most of the jar, but not by the movement merely of the pillar C in a parallel direction with the pillar D, but the upper end is permitted by the longer link to take a slight coincident motion away from the pillar D and the fork B and the wheel A to yield backward considerably, and thus doubly yield to the obstruction; and a similar effect is produced when the obstruction is to the rear wheel, or when the jolt causes an action of 55 the pillar D it is accompanied by a slight change of base of the machine.

I get a long secure mechanism by placing the fore-and-aft links K L quite a distance apart, and this is permitted by my construction of an intermediate bracket P, carrying the lug for the upper steering-center. By 60 making this bracket or encircling lug in-

gral with the lug O² and the arms and stop P' P², I secure strength and economy and lightness. The spring R is held securely in 70 position by the method of attaching its ends to the lug C', and holding its opposite part by the stops P², and by means of the long branches and coils I obtain a very resilient spring of sufficient power, but permitting 75 much play.

By my construction of the brake mechanism I secure greater directness and efficiency with less friction. In operating it, the rider squeezes upward on the handle g', which, by 80 the action of the intermediate parts, presses downward the back arm of the rocking link G⁴, and thus pulls upward on the connecting-rod G⁶ and forces the spoon G⁹ against the tire. When the hold of the rider's hand is 85 released from the brake-handle, the disengaging-spring g, between the handle-bar and the brake-handle lever, reverses this operation of the parts and releases the brake. By this division of the downward connecting-rods and 90 the interposition of the rocking link pivoted on the fore-and-aft link K, I provide for the vertical motion of the handle-bar and brake-handle lever under the yielding action of the 95 spring and the links in such manner that the brake-spoon G⁹ is not affected by the change in height of the brake-handle lever within such limits as are provided for it, nor is the application of the brake affected by any such 100 variation in height of the handle-bar and 100 brake-handle lever, owing to obstructions encountered when the brake is on.

It is obvious that substantial parts of my improvements may be used without using the whole, and that modifications in the form 105 and arrangement of the parts may be effected without departing from the substance of my invention—as, for example, the spring R may be made in two parts instead of one piece of wire, and different forms of springs 110 may be used; or different forms of lugs and branches may be used; or the fork may be connected with the under pillar or the handle-bar support with the forward pillar; or the forward pillar, instead of being connected directly to the fork and extending vertically 115 above it, may be connected at a distance by intervening mechanism, or the spring and stops and link mechanism and the two pillars may be used in other parts of the machine; but I have described the one in which 120 I think my improvements are best embodied.

I claim as new and of my invention—

1. In a velocipede-spring-frame mechanism having a fore pillar and an after pillar 125 and connecting-links and a limiting-spring, the upper pair of links, as K K, longer than the lower pair, as L L, and constructed and combined essentially as set forth.

2. In a velocipede-spring-frame mechanism having a fore pillar and an after pillar 130 and connecting-links and a limiting-spring, the tubular after pillar, as D, the encircling transverse lug, as D', a lower center lug, as

O', and the intermediate encircling lug P, and the upper center lug, as O², constructed and combined substantially as set forth.

3. In a velocipede-spring-frame mechanism having a fore pillar and an after pillar and connecting-links and a limiting-spring, the upper center lug O², constructed and combined between the transverse lugs and the upper and lower links, essentially as set forth.

10 4. In a velocipede-spring-frame mechanism having a fore pillar and an after pillar and connecting-links, a spring, as R, with its ends R⁵ R⁵ secured to one of the pillars, and its middle part bent to form a loop, as R', above the same, and with the arms, as R² R², operating against stops, as P² P², connected to the other pillar, and with the coils R³ R³ and arms R⁴ R⁴, substantially as shown and described.

20 5. In a velocipede-spring-frame mechanism having a brake mechanism with the handle-lever at the handle-bar and connected with one portion of the frame and having the brake-spoon lever connected with another portion of the frame, a connecting rod or rods, as G³ G⁶, and a rocking link, as G⁴, pivoted at

or near the center of motion between the two parts of the frame, and constructed and combined to operate essentially as set forth.

6. In a velocipede-spring-frame mechanism having a fore pillar and an after pillar and connecting-links and a limiting-spring, and having a brake mechanism with the handle-lever connected with the handle-bar and with one of the pillars, and having a brake-spoon lever connected with the other pillar, connecting-rods, as G³ and G⁶, and a rocking link, as G⁴, pivoted at a point between the pillars, and constructed and combined essentially as set forth.

30 7. The combination of the handle-bar and supporting mechanism and fork of a velocipede, a brake-handle lever, as G, fulcrumed in a bracket on the under side of the handle-bar, jointed connecting-rods, as G³ G⁶, rocking 35 link, as G⁴, and brake spoon and lever, as G⁵ G⁹, constructed and combined to operate essentially as set forth.
